Application filed August 3, 1895. Serial No. 558,169. Term of patent 3½ years.

To all whom it may concern:

Be it known that I, JOHN B. NEIL, residing at New York, county of New York, State of New York, have invented and produced a new and original Design for a Pattern to be wrought into Wilton and other Carpetings, in such coloring as may be designed; and I do hereby declare that the drawing accompanying this specification gives and conveys to any one skilled in the art of carpet weaving and manufacture a clear understanding of the same, and is sufficient to enable such person to use my invention.

The design consists of the body A and the border B.

The body A shows conventionalized flower and bead work arranged in curved forms.

The border B has principally the same character of conventionalized flower and bead work as in body, but arranged in larger curves and scrolls.

What I claim as my invention, and desire to secure by Letters Patent, is—

1. In a design for a carpet the body A, substantially as shown.
2. In a design for a carpet the border B, substantially as shown.
3. The design for carpets, consisting of the body A, and the border B, substantially as shown.
